DESIGN FOR A COMBINATION TOILET SEAT COVER AND BATH MAT OR SIMILAR ARTICLE

Carol Zito, New York, N. Y.

Application October 28, 1939, Serial No. 87,908

Term of patent 3½ years

To all whom it may concern:

Be it known that Carol Zito, citizen of the United States and resident of New York city, in the county of New York, State of New York, has invented a new, original, and ornamental Design for a Combination Toilet Seat Cover and Bath Mat or Similar Article, of which the following is a specification, reference being had to the accompanying drawing, forming part thereof, and in which,

Fig. 1 is a perspective view of a combination toilet seat cover and bath mat, embodying my new design, showing the same flattened out;

Fig. 2 is a perspective view of the same folded.

I claim:

The ornamental design for a combination toilet seat cover and bath mat or similar article, substantially as shown.

CAROL ZITO.
